BUCKLE

Alfred Laurain, Paris, France, assignor to Société
du Caoutchouc Manufacturé, Paris, France

Application March 16, 1934, Serial No. 715,970
In France March 27, 1933

10 Claims. (Cl. 24—191)

This invention relates to buckles and has for its primary object to provide a simple and compact buckle particularly designed for use on garment suspenders, garters, waist belts, etc., although also utilizable upon valises, trunks or more generally wherever it is desirable to clamp together several straps while keeping the possibility of readily adjusting them with respect to one another for instance to vary the useful length of a strap loop.

A further object of the invention is to provide a buckle having no undue thickness and which can be easily adjusted along the straps in both directions without injuring them even if such straps have a rough or ribbed surface such as is frequently the case for elastic webbings used on trouser suspenders, braces or garters.

A still further object of the invention is to provide a buckle which will not bite into the straps and will nevertheless firmly clamp them in the selected position of adjustment so as to prevent any undue displacement of said straps even under heavy tractional stresses such as the ones to which suspender straps or webbings are exposed.

With these and such other objects in view as will incidentally appear hereafter, the invention comprises the novel features of construction and combinations of parts that will now be hereafter more fully described and pointed out in the claims.

In the accompanying diagrammatic drawing are shown by way of constructional examples preferred embodiments of the invention.

Figure 1 is a perspective view showing the front face of the buckle, assuming the pivotal flap being rocked down.

Figure 2 is a view similar to Figure 1, assuming the pivotal flap being rocked up, the anti-friction cross strip being clearly shown.

Figure 3 is a perspective view showing the rear face of the buckle.

Figure 4 is an edge view of the buckle shown in Figures 1 to 3.

Figure 5 is an edge view of a modification of the buckle, the anti-friction cross strip being pivotally supported between the sides of the buckle yoke.

Figure 6 is a perspective view of the buckle shown in Figures 1 to 4, showing the engagement of the two straps through the slots located on both sides of the anti-friction cross strip.

Figure 7 is an edge view of the modified buckle shown in Figure 5 showing the engagement of

two ribbed webbings through the slots located on both sides of the anti-friction cross strip journaled between the sides of the buckle yoke.

Like reference numerals and characters designate like parts throughout the several views.

1, 2 designate the parallel sides of a yoke forming the body of the buckle. This yoke may be advantageously formed of a rigid material such as a metal or alloy, preferably of stainless composition or suitably coated for withstanding moisture or sweat. The sides 1, 2 are connected to each other adjacent one of their ends by a cross bar 3 having an elongated slot 4 to receive a strap S¹. Adjacent their opposite ends, the yoke sides 1, 2 are connected by a cross rod 5.

Intermediate their ends, the yoke sides 1, 2 are furthermore connected by a cross strip or tie 6 which defines on its opposite sides two contiguous co-planar slots 7, 8 extending substantially over the full width of the yoke. The upper slot 7 is defined between the cross strip 6 and the cross rod 5, while the lower slot 8 is defined between the cross strip 6 and the cross bar 3.

In the upper slot 7 is slidably engaged a strap S² which can thus be slid under the cross rod 5. In the lower slot 8 is slidably engaged the strap S¹. As this strap S¹ is already engaged through the slot 4 in the lower cross bar 3, it is firmly jammed due to its double bend and thus firmly held in the buckle. Thus this strap S¹ may be the stationary free end of a suspender webbing.

The cross strip or tie 6 is thus interposed flatly between the reaches of the straps S¹, S² located in the contiguous slots 7, 8, so that it prevents any mutual contact of said straps at their adjacent positions. Moreover, the cross strip or tie 6 is made of an anti-friction material, for instance of a polished metal or other smooth substance. As a result of this, the straps S¹, S² may be slid through their respective slots 7, 8 without undergoing any substantial friction, which considerably facilitates their adjustment even if said straps are formed of a ribbed or corrugated webbing or fabric as it is frequently the case for highly elastic suspender webbings having a core of rubber threads or strands and textile warp and weft threads so bound together as to form a ribbed covering on both sides of the core.

In the embodiment shown in Figures 1 to 4, the anti-friction cross strip or tie 6 is integral with the sides 1, 2 of the buckle yoke, the angular position of said cross strip or tie being arranged for enabling the same to fulfill its purpose as above-stated.

In the embodiment shown in Figures 5 and 7,

the cross strip or tie 6' is constituted by a separate elongated strip or sheet of anti-friction or smooth material (for instance of celluloid or the like) having end trunnion-like projections 6'' which are pivotally received in holes 1', 2' formed in the yoke sides 1, 2. In this embodiment, the angular position of the cross strip or tie 6' can conform itself by a pivotal motion to the sliding displacements of the straps S¹, S² in the slots 8, 1, for instance when the strap S² is slid through the upper slot 7 while the strap S¹ is held in the lower slot 8.

The cross strip or tie 6 or 6' may have a certain amount of inherent resiliency or flexibility so as to give way or lend itself to a certain extent when either the strap S¹ or the strap S² is engaged through the slot 8 or the slot 1 preparatory to the use of the buckle or when the strap S² is adjusted through the upper slot 7. This action takes place when for instance (assuming the straps S¹, S² being the webbings of a trouser or hose suspender) the webbing S² is adjusted through the slot 7 while the webbing S¹ is held stationary in the buckle, for the purpose of regulating the useful length of said suspender.

Straddling the cross rod 5 is a V-shaped flap having unequal legs 9, 10 and end lugs 11, 12 each of which is rolled upon itself to form a journal which encompasses or circumscribes a portion of the cross rod 5. By this arrangement, the flap 9-10 can be rocked relative to the yoke about the cross rod 5. This flap 9-10 is shown in rocked down position in Figure 1 and in rocked up position in Figure 2.

When in rocked down position as shown in Figure 1, the V-shaped flap 9-10 covers the upper slot 7 and cross strip 6 so that its longer fore leg 9 clamps the strap S² in said slot 7 while its shorter rear leg 10 assists in clamping said strap by engaging its portion situated just to the rear of the yoke. The strap S² is thus prevented from unduly sliding through the slot 7. In the event of a buckle for a garment suspender, this clamping action of the flap 9-10 prevents any undue creeping motion of the buckle along the suspender webbing.

The angularity of the legs 9, 10 of the rockable flap of the buckle is such that its longer fore leg 9 cannot be rocked up into the position shown in Figure 7 without overcoming a resistance due to the rubbing action of the shorter rear leg 10 which acts, as it were, as a cam against the strap S². This resistance locks the flap in rocked down position, so that no undue disengagement of the strap S² by the flap is likely to take place.

It will be seen that the invention provides a simple, compact and rugged buckle for straps or webbings of every kind which is self-locking while being readily adjustable after having been manually unlocked by a very simple motion.

What I claim is:—

1. A buckle comprising a yoke, a flat anti-friction cross strip connecting the sides thereof and defining two contiguous co-planar slots for the respective engagement of two straps slideable through said yoke, said cross strip being intercalated flatly between the contiguous reaches of the straps located in the slots for preventing mutual contact of said strap reaches, and a flap pivotally connected at one end to the yoke sides, this flap freeing the strap engaged through the slot adjacent its pivotal connection in one angular position and clamping said strap in said slot in another angular position.
2. A buckle comprising a yoke having parallel

sides connected at one end by a slotted cross bar, a flat anti-friction cross strip connecting said sides intermediate their ends and defining two contiguous co-planar slots for the respective engagement of two straps slideable through said yoke, said cross strip being intercalated flatly between the contiguous reaches of the straps located in the slots for preventing mutual contact of said strap reaches, and a flap pivotally connected to the other end of the yoke, this flap freeing the strap engaged through the slot adjacent its pivotal connection in one angular position and clamping said strap in said slot in another angular position.

3. A buckle comprising a yoke having parallel sides connected at one end by a cross bar and at the other end by a rod, a smooth flat cross tie spanning the gap between said sides intermediate their ends and delineating two contiguous co-planar slots for the respective engagement of two straps slideable through said yoke, said cross tie being intercalated flatly between the contiguous reaches of the straps located in the slots for preventing mutual contact of said strap reaches, and a flap pivotally connected to said rod, this flap freeing the strap engaged through the slot adjacent its pivotal connection in one angular position and clamping said strap in said slot in another angular position.

4. A buckle comprising a yoke, a flat anti-friction cross strip connecting the sides thereof and defining two contiguous co-planar slots for the respective engagement of two straps slideable through said yoke, said cross strip being intercalated flatly between the contiguous reaches of the straps located in the slots for preventing mutual contact of said strap reaches, and a V-shaped flap pivotally connected to the yoke sides at one end of the yoke and having unequal legs, this flap freeing the strap engaged through the slot adjacent its pivotal connection in one angular position and clamping said strap in said slot in another angular position.

5. A buckle comprising a rigid yoke, a flexible anti-friction flat cross strip connecting the sides thereof and defining two contiguous co-planar slots for the respective engagement of two straps slideable through said yoke, said cross strip being so angularly disposed relative to said sides as to be intercalated flatly between the contiguous reaches of the straps located in the slots for preventing mutual contact of said strap reaches, and a V-shaped flap pivotally connected to the yoke sides at one end of the yoke, this flap being so sized as to free the strap engaged through the slot adjacent its pivotal connection in one angular position and clamping said strap in said slot in another angular position.

6. A buckle comprising a yoke having parallel sides connected by a rod, a flat anti-friction cross strip connecting the yoke sides and defining two contiguous co-planar slots for the respective engagement of two straps slideable through said yoke, said cross strip being intercalated flatly between the contiguous reaches of the straps located in the slots for preventing mutual contact of said strap reaches, and a V-shaped flap having end journals circumscribing the yoke rod, this flap freeing the strap engaged through the slot adjacent the rod in one angular position and clamping said strap in said slot in another angular position.

7. A buckle comprising a yoke having parallel sides, a smooth anti-friction cross strip pivotally carried between said sides, said cross strip defin-

ing two contiguous co-planar slots for the respective flat engagement of two straps slideable through said yoke, said cross strip being disposed to prevent contact between the parts of said straps located in the slots, and a flap pivotally connected to the yoke sides at one end of the yoke, this flap freeing the strap engaged through the slot adjacent its pivotal connection in one angular position relative to the yoke and clamping said strap in said slot in another angular position.

8. A buckle comprising a rigid yoke having parallel sides, a smooth anti-friction cross strip having end trunnions engaged in holes in said sides, said cross strip defining two contiguous co-planar slots for the respective flat engagement of two straps slideable through said yoke, said cross strip being sized and disposed to prevent contact between the parts of said straps located in the slots, and a V-shaped flap whose apex is pivotally supported between the yoke sides at one end of the yoke, this flap freeing the strap engaged through the slot adjacent its apex in one angular position relative to the yoke and clamping said strap in said slot in another angular position.

9. A buckle comprising a yoke having parallel sides connected at one end by a slotted cross bar and at the opposite end by a cross rod, a smooth anti-friction flat cross strip connecting the yoke sides intermediate their ends and defining two contiguous co-planar slots between said strip and said rod and bar respectively, said contiguous slots being respectively intended to slidably receive two straps such as suspender webbings, one of these straps being received in the cross bar slot, said cross strip being intercalated flatly between the contiguous reaches of the straps located in the slots for preventing mutual contact with said strap reaches, and a V-shaped flap having end journals circumscribing the cross rod, the legs of this flap being of unequal length and disposed for freeing the strap engaged through the slot adjacent the cross rod in one angular position relative to the yoke, while said legs clamp said last-named strap in the last-named slot in another angular position.

slots being intended respectively to slidably receive two straps such as suspender webbings, said cross strip being intercalated flatly between the contiguous reaches of the straps located in the slots for preventing mutual contact of said strap reaches, and a V-shaped flap having end journals circumscribing the cross rod, this flap freeing the strap engaged through the slot adjacent the rod in one angular position and clamping said strap in said slot in another angular position.

10. A buckle comprising a yoke having parallel sides connected at one end by a cross bar slotted to receive a strap and at the opposite end by a cross rod, an anti-friction flat cross strip connecting the yoke sides intermediate their ends and defining two contiguous co-planar slots between said strip and said rod and bar respectively, said contiguous slots being respectively intended to slidably receive two straps such as suspender webbings, one of these straps being received in the cross bar slot, said cross strip being intercalated flatly between the contiguous reaches of the straps located in the slots for preventing mutual contact with said strap reaches, and a V-shaped flap having end journals circumscribing the cross rod, the legs of this flap being of unequal length and disposed for freeing the strap engaged through the slot adjacent the cross rod in one angular position relative to the yoke, while said legs clamp said last-named strap in the last-named slot in another angular position.

ALFRED LAURAIN.
